PARTITIONS FOR BOXES

Cyril F. Bowen, Montreal, Quebec, Canada, assignor to G. & J. Esplin Limited, Montreal, Quebec, Canada

Application November 15, 1948, Serial No. 59,993
In Canada October 12, 1948

1 Claim. (Cl. 217—22)

1

This invention relates to improvements in wooden boxes and more particularly to partitions for boxes intended for use as shipping and/or carrying cases for bottled goods.

One object of this invention is to provide a lightweight bottle carrying case with a reinforced partition wall adapted to serve as a carrying handle for the case, said wall being reinforced to prevent breakage of the partition wall where it has been weakened by reason of the provision of a hand grip opening.

Another object is to provide a box of the character described with a cell-forming filler in which a central transverse partition of the filler serves as a carrying handle for the box, said transverse partition having a hand grip opening in the upper section and having reinforcing elements extending from its upper edge downwardly to strengthen the partition on either side of the hand grip opening.

The above and other objects and characteristic features of this invention will be more readily understood from the following detailed description taken in connection with the accompanying drawings, in which—

Fig. 1 is a plan view of a box employing my invention.

Fig. 2 is an end view of the box shown in Fig. 1.

Fig. 3 is a perspective view of the partition and filler.

Fig. 4 is a section view of the partition and filler shown in Fig. 3.

Referring more particularly to the drawings, my improved box comprises side walls 5, end walls 6, and a bottom wall 7. Each of the side and end walls consists of a single panel of wood veneer having component plies P adhesively secured together by any suitable waterproof adhesive. The bottom wall 7 is here shown as being the slatted type comprising spaced slats 7a which may be either of solid wood or wood veneer adhesively secured together by waterproof adhesive.

A plurality of cleats, comprising horizontally extending top and bottom cleats 8 and 9 and vertically extending side cleats 10, are secured to the outer side of each end wall panel 6. These cleats are arranged in rectangular arrangement to lie flush with the edges of panel 6.

The end portions of side walls 5 are fastened by nails 11 to side cleats 10 and to the end portions of top and bottom cleats 8 and 9. Slats 7a are fastened by nails 12 to the underside of cleats 9.

A reinforcing strap 15 is fastened to each end

5 of the box by the fastening elements 11 and 12 so that each strap extends across the bottom wall 7 and upwardly along side wall panels 5. The upper portions 15a of each strap are bent inwardly over the adjacent end wall cleat 8 and fastened thereto by fastening elements 16. The inner extremities of upper strap portions 15a are bent downwardly as indicated at 15b and fitted in slots 17 provided in cleats 8. The end wall panels 6 are provided with hand openings 6a adjacent the lower edges of top cleats 8 carried by the panels 6.

15 This box is shown fitted with a cell forming filler 18 consisting of longitudinally extending partitions 19 suitably interlocked with transversely extending partitions 20 and 21. Each of the partitions 19 and 20 consists of a strip of plywood veneer but may be of any suitable lightweight material such as a thin strip of solid wood. Partition 21 is here shown to be solid wood of a substantial thickness and is located centrally of the box. In the preferred construction, partition 21 is in two sections, the lower section being designated 22 and the upper section being designated 23.

20 Partitions 19, 20 and the lower section 22 of partition 21 are respectively provided with slotted portions 19a, 20a and 21a, so that in the assembled relation of the partitions as shown, the upper and lower edges of the longitudinally extending partitions 19 are elevated above the corresponding edges of transverse partitions 20. The lower edge 21b of section 22 of partition 21 is arranged to lie flush with the lower edges of transverse partitions 20 and the upper edge 21c of this partition is arranged to lie flush with the upper edges of longitudinally extending partitions 19. This arrangement of the partition section 22 assures direct support of partition 21 along its lower edge 21b on the bottom wall 7 of the box. Similarly, if it is desired to invert the filler in the box, the partition 21 is supported along its edge 21c on the bottom wall of the box.

25 As shown in the drawings, the upper section 23 of partition 21 is supported along its lower edge by the upper edge 21c of lower section 22 and has its upper edge substantially flush with the upper edges of the opposing side walls 5 of the box. The partition 21 is secured along its side edges to the opposing side walls 5 by fastening elements 24 and is provided with a hand opening 25 located a convenient distance below the upper edge of the partition to permit lifting of the box by the partition 21.

30 The upper section of partition 21 is strength-

ened in the vicinity of the hand opening by reinforcing elements 27 which extend downwardly a substantial distance from the upper edge of the partition adjacent either end of the hand opening. The reinforcing elements here shown comprise elongated spikes which are driven into the wood from the top of the partition, and penetrate the wood for a substantial distance below the hand opening. The reinforcing element may comprise any suitable elements which would conveniently strengthen the upper section of the partition at either ends of the hand opening against splitting of the wood through the hand opening section thereof which may have become weakened in providing the hand opening. For example, wooden pins may be inserted in suitable vertical recesses in the partition or the reinforcing elements may be placed externally from the top of the partition for a substantial distance along either surface of the partition adjacent the ends of the hand opening.

By reason of the fact that the slotted portions 21a of partition section 22, as here shown, extend from the upper edge 21c downwardly, it is necessary to divide the partition into separable upper and lower sections. However, when the filler is inverted the slots 21a are likewise inverted. In this case partition 21 may constitute separate upper and lower sections or may constitute a single panel partition, the lower portion of which is suitably slotted to interlock with the slotted portions of the longitudinally extending partitions 19.

Having thus described what is now considered to be the preferred embodiment of the invention, it will be readily understood that various modifications may be resorted to without departing from the scope and spirit of my invention as defined by the appended claim.

I claim:

In a box of the character described, including side, end and bottom walls, and a cell forming filler formed by a plurality of relatively thin longitudinally and transversely extending partitions, each of said partitions being provided with co-operating elongated slots adapted to receive substantial portions of the other in interlocking engagement with each other, said transverse partitions having lower marginal portions projecting downwardly a substantial distance below the lower marginal edges of the longitudinal partitions, and said longitudinal partitions having upper marginal portions projecting upwardly a substantial distance above the upper marginal edges of the said transverse partitions, and ter-

minating a substantial distance below the upper marginal edges of said box, a relatively thick, continuous partition wall arranged centrally and transversely of said box intermediate two of said thin transverse partitions, said continuous wall including a lower panel section provided with elongated slots adapted to receive slotted portions of said longitudinally extending partitions in interlocking engagement with each other, said lower panel section having its lower marginal edge lying in a common horizontal plane with the lower marginal edges of said thin transversely extending partitions and being directly supported by the bottom wall of said box and having its upper marginal edge lying in a common horizontal plane with the upper marginal edge of said longitudinally extending partitions, and a separable upper panel section directly supported along its lower edge by the upper edge of said lower panel section, securing means extending through the side walls of said box and into the side edges of said upper panel section to retain the latter and the underlying lower panel section against vertical displacement, said upper panel section being provided with a hand grip opening suitably spaced below the upper edge thereof to define an integrally moulded hand grip between said opening and the upper edge of the panel, and reinforcing elements in the upper panel section at opposite ends of said hand grip opening, said reinforcing elements extending downwardly through the upper edge thereof and terminating a substantial distance below the horizontal plane of the lower defining wall of said opening to reinforce the areas of the panel on either side of the hand opening which have been weakened as a result of the provision of said hand opening.

CYRIL F. BOWEN.
